[57] CLAIM

The ornamental design for a transaction terminal console and swivel stand, as shown and described.

DESCRIPTION

FIG. 1 is a perspective view of a transaction terminal console and swivel stand showing my new design;

FIG. 2 is a top plan view of the transaction terminal console and swivel stand shown in FIG. 1;

FIG. 3 is a front elevational view of the transaction terminal console and swivel stand in FIG. 1;

FIG. 4 is a rear elevational view of the transaction terminal console and swivel stand shown in FIG. 1; and,

FIG. 5 is a right side elevational view of the transaction terminal console and swivel stand shown in FIG. 1.

The left side elevation view of the transaction terminal console and swivel stand shown in FIG. 1 is a mirror image of the right side elevational view shown in FIG. 5.

The bottom side of the transaction terminal console and swivel stand is unornamented and forms no part of my invention.
